UNITED STATES PATENT

THOMAS F. CRAWLEY, OF NEWTON, MISSISSIPPI.

AUTOMATIC CARRIAGE-RETURN FOR TYPE-WRITERS, LINE-SPACERS, AND REVERSE TABULATORS.

1,251,867.

Specification of Letters Patent.

Patented Jan. 1, 1918.

Application filed October 16, 1915. Serial No. 56,278.

To all whom it may concern:

Be it known that I, THOMAS F. CRAWLEY, a citizen of the United States, residing at Newton, in the county of Newton and State of Mississippi, have invented certain new and useful Improvements in Automatic Carriage-Returns for Type-Writers, Line-Spacers, and Reverse-Tabulators, of which the following is a specification.

My invention relates to typewriters and more particularly to an improved automatic carriage return.

The primary object of my invention is to provide a device of the character above mentioned in which, when the carriage of a typewriter has reached the end of its travel or the completion of a line, it will automatically return to its original position, ready to start another line.

Another object of my invention is to provide a carriage returning mechanism which automatically spaces the paper carrying roller simultaneously with the return of the carriage.

A further object of the invention is to provide improved circuit closing means for use in connection with a device of the character of my invention.

A still further object of my invention is to provide a new and improved clutch member for association with the preferred embodiment of my invention.

With the above and other objects in view my invention resides preferably in the construction, combination, and arrangement of parts as hereinafter set forth in the specification as illustrated in the accompanying drawings, in which—

Figure 1 is a front elevational view of a typewriter showing my improvements associated therewith,

Fig. 2 is a rear elevational view of the same,

Fig. 3 is a diagrammatic view of a circuit arrangement,

Fig. 4 is a longitudinal sectional view of an improved clutch which I use in connection with my improved typewriter carriage return, and

Fig. 5 is a detail end elevational view of an electric motor showing the manner of mounting parts of the invention hereinafter described.

Similar reference characters designate

similar parts throughout the various views 55 of the drawings.

In the drawings, I have illustrated a typewriter having the usual base frame 1 on which the carriage 2 is laterally movable. My invention is so arranged as to permit its 60 application to any of the present typewriters. The invention embodies broadly an electric motor, circuit closing means on the carriage, means for maintaining the circuits in closed position throughout the return of 65 the carriage and means for automatically opening the circuits at the end of the return of said carriage. An improved automatically acting one-way clutch is provided for a purpose which will hereinafter appear, 70 the detail structure of this clutch being hereinafter described.

More specifically, the invention embodies an electric motor 3, the armature shaft 4 thereof being elongated as shown to advantage in Fig. 4 to carry a winding sheave or drum or the like having my improved clutch associated therewith. The clutch is designated as a whole in Fig. 1 by the reference numeral 5. The electric motor 80 3 is connected to the carriage through the medium of a belt, twine or the like 6, said belt having one extremity wound about the clutch 5 and the other extremity connected to the line spacing lever 7 of the typewriter. 85 The belt 6 is trained over the guide pulley 8 mounted on a bracket 9 carried by a base frame 1 of the typewriter.

In order to energize the motor to cause a return of the carriage automatically, I have 90 provided a source of electrical energy such as a battery 10, conductors 11 and 12 leading therefrom, one of said conductors having the electro-magnet 13 interposed therein and the other conductor being electrically 95 connected with an armature 14 adapted to be influenced by the electro-magnet when the latter is energized. One extremity of the armature 14 is rigidly mounted on an insulator 15, the free extremity of said armature being bent upwardly and provided with a ball contact 16. The motor 3 is embraced in the branch circuit including the conductors 17 and 18, the conductor 18 having a circuit closer 19 interposed therein, said circuit closer being carried by the armature 14. 100 A second circuit closer 20 is carried by the armature 14 and is adapted to contact with 105

the terminal 21 of a branch conductor 22 connected to the conductor 23 thence leading to the resilient arm 24 carried by the carriage of the typewriter. A second branch 5 conductor 25 is connected to the main conductor 11 and terminates in the stationary terminal 26 disposed in the path of movement of the resilient arm 24 so as to be engaged thereby to close the circuit to the electro-magnet 13. It will be seen from an 10 inspection of Fig. 3 that the circuit closer 19 is adapted to engage the circuit terminal 27. A manually operable circuit closer 28 is shunted across the circuit closer 19 and the 15 circuit closer 27 for a purpose which will hereinafter appear, said terminal 28 being termed hereinafter the spacing key. A manually operable circuit closer 29 is shunted across the conductors 23 and 25 to 20 permit the manual closing of the circuit of the electro-magnet in case of emergency. From the above, it will be seen that a main 25 circuit is provided, having a pair of branch circuits extending therefrom, one of said branch circuits embracing the electric motor 3 and the other of said branch circuits serving to maintain the motor circuit closed for a predetermined interval.

As shown to advantage in Fig. 2, the 30 resilient arm 24 is adjustably carried by the carriage 2 so as to adjust the length of travel of the carriage.

In order to automatically open the 35 circuits when the carriage has been returned, I provide a circuit opener comprising a lug or button 30 slidably adjustable on a rod 31 supported on the carriage 2.

In order to facilitate a release of the carriage for use after the same has been 40 returned to its starting position, I have provided an improved clutch comprising a winding drum 32 elongated as at 33 and provided with a concentrically arranged relatively large opening 34. The drum 32 45 is threaded for engagement with the extension 35 of the armature shaft 4, of the electric motor 3, or said drum may be mounted separate from the motor extension and carried thereby. The extension 35 is 50 automatically engageable and disengageable with and from said drum, the threaded portion being designated 36. A flanged collar 37 may be carried by the extension 35 and freely rotatable thereon, an adjustable collar 38 carried on the extension 35 serving to 55 limit the longitudinal movement of said drum. Suitable anti-friction bearing means 39 may be interposed between the collars 38 and 37. A cap 40 is mounted for free rotation on the extension 35, said cap being maintained in the desired position thereon by means of an adjustable collar 41. Suitable anti-friction bearing means 42 may be 60 interposed between the cap 40 and the collar 41. A suitable coil spring element 43 is inter-

posed between the drum 32 and the cap 40, the cap 40 having a recess 44 to receive said spring, and said cap being receivable in the recess 34 formed in the drum. A ratchet wheel 45 is mounted on the extension 35 70 and is adapted to rotate therewith, a pawl 46 pivotally mounted on the motor frame having engagement with said ratchet wheel to permit rotation in but one direction. A suitable guard 47 is arranged on the motor 75 frame and is secured thereto as at 48 the upper end of the same being adapted to be engaged over the pulley 8 and the drum 32 in order to prevent dislodgement of the belt 6.

In operation, the typewriter is used in the usual manner, the carriage traveling across the machine step by step until the spring terminal 24 engages the stationary terminal 26. This will close the main 85 circuit in which the electro-magnet 13 is interposed energizing said magnet and causing the armature 14 to be actuated. This operation automatically closes two circuits, viz., the motor circuit and the main circuit, the 90 latter being permanently closed by the above mentioned operation. The current flows at this time through a conductor 12 to the electro-magnet 13 thence through the conductor 22 passing from the terminal 21 to 95 the armature 14 at the point 20 and thence through the conductor 11 back to the source of energy 10. The motor circuit includes the conductor circuit 17 connected to the conductor 12, the conductor 18, from the 100 terminal 27 through to the circuit closer 19 and thence through the conductor 11 back to the source of energy. When the motor is energized, the motor will, of course, revolve, winding the belt 6 on a drum 32 105 and causing the typewriter carriage to be automatically returned to the starting position, the spacing lever 7 being caused to operate automatically. The circuit opener 30 carried by the carriage 2 serves to automatically open the circuits hereinbefore referred to when the carriage is brought to the position at which said circuit opener is caused to engage the knob 16 carried by the armature 14 causing the latter to be raised breaking 115 the circuits at the points 19 and 20. This will automatically open both the motor circuit and the main control circuit and the carriage is ready for further movement through its path of travel. Should it be desired to move the carriage independently of the automatic control, it is merely necessary to close the circuit closer 29, for an instant, which will cause the carriage to return. In order to operate the spacing lever independently of the carriage, I have provided the spacing key 28 hereinbefore referred to. By intermittently closing said spacing key, a short quick pull may be directed on the belt 6 causing the lever 7 to be actuated. 120 125 130

When the carriage reaches the end of its travel and is released, it is necessary that some means be provided to permit the free rotation of the drum 32. The threads 36 to 5 which said drum is engaged, are formed on an extension 35 in a direction opposite to the direction of rotation of said drum when winding. Thus, when the drum is unwinding, owing to the movement of the carriage, 10 the said drum will be caused to travel longitudinally along the extension 35 against the tension of the spring 43. It is to be understood that the spring 43 serves to normally tend to force said drum into engagement 15 with the threads 36 so that when the shaft is rotated by the automatic closing of the several circuits hereinbefore described, the drum will be caused to wind the cord thereon. Of course, it will be understood that 20 the number of threads may be varied as desired depending on the relation of the size of drum and the length of travel of the carriage.

From the above description taken in connection with the accompanying drawings, it is thought that a clear and comprehensive understanding of the construction, operation and advantages of my invention may be readily gathered and while I have shown 30 and described the same as embodying a specific structure, I reserve the right to make changes therein which do not depart from the spirit and scope of the invention as claimed.

35 What I claim is:

1. A carriage return for typewriters, including, in combination with a typewriter having the usual carriage, an electric motor mounted on said typewriter and having 40 connection with said carriage, said motor being embraced in a branch circuit communicating with a main circuit, means on the typewriter carriage for automatically closing said main circuit, and means embraced in said main circuit for maintaining the same closed and for closing said motor circuit.

2. A carriage return for typewriters, including, in combination with a typewriter having the usual carriage, an electric motor mounted on said typewriter and having connection with said carriage, a motor embraced in a branch circuit communicating with a main circuit, means on the typewriter carriage for automatically closing said main circuit, and means for maintaining the same closed and for

closing said motor circuit, and means carried by the carriage for automatically opening said circuit closer when the carriage is returned to the starting position. 60

3. A carriage return for typewriters, including, in combination with a typewriter having the usual carriage thereon, a main circuit, said main circuit embracing an electromagnet and circuit closer; a branch circuit embracing an electric motor and having electric connection with said main circuit, a circuit closer for said branch circuit adapted for actuation by said electro-magnet, 65 whereby to close said main circuit and said branch circuit when said main circuit is initially closed.

4. A carriage return for typewriters, including, in combination with a typewriter having the usual carriage thereon, an electric motor on said typewriter having connection with said carriage, a motor circuit embracing said motor and a circuit closer, a main circuit having an electro-magnet embraced therein, and a circuit closer carried by the carriage, said electro-magnet being adapted to actuate said circuit closer in the motor circuit to maintain said motor circuit closed until the carriage has been returned to the starting position. 75

5. A carriage return for typewriters, including an electric motor, a circuit therefor, a main circuit electrically connected with said motor circuit, an electro-magnet interposed in said motor circuit, a circuit closer adapted to be actuated by said electro-magnet, adjustable means carried by the carriage to close said main circuit, said circuit closer serving to maintain said main circuit and 90 said motor circuit closed throughout the return travel of said carriage.

6. A carriage return for typewriters, including an electric motor, the armature shaft of said motor being extended and threaded, retaining collars carried on the shaft, a winding drum adapted at times to freely move on said shaft, means for causing said drum to automatically engage and rotate with said shaft, and a flexible element 100 adapted to be wound about said drum and connected to the typewriter carriage, as and for the purpose set forth. 105

In testimony whereof I affix my signature in presence of two witnesses.

THOMAS F. CRAWLEY.
